UNITED STATES PATENT OFFICE

MICHAEL J. McHALE, OF SCRANTON, PENNSYLVANIA

FLYER CONSTRUCTION

Application filed May 31, 1930. Serial No. 458,210.

This invention relates to flyers for spinning machines and more particularly to one having completely replaceable parts.

Hitherto it has been proposed to use flyer blocks made of wood and brass.

These constructions require that the flyer wires be permanently associated therewith, which condition precludes the replacement of the wires as they break in service, due to the continued abrasive effect of the threads passing therethrough. In addition, mill nuts or other like devices are often required to hold the flyer blocks in place on the spindles. Where self-contained springs held in place by bushings have been used, the disadvantage of the mill nut has been obviated but the re-wiring of such devices is, in every instance, a custom job. Where devices of the type shown in the patent to H. E. Herr #1,614,552 have been used, considerable difficulty has been experienced with the maintenance and repair of these devices, due to the fact that special tools are required for the assembling steps, in order to remove broken wires and replace them with new ones, and, in addition, the expansion anchoring sleeves frequently break and cannot be replaced, thus requiring scrapping of the entire unit.

It is an object of the present invention to provide a flyer for spinning purposes which is composed of a plurality of replaceable parts.

It is another object of this invention to provide an improved flyer of the type described which is freely movable and provided with replaceable parts throughout.

Yet another object of this invention is the provision of a novel flyer construction in which the flyer wires or arms serve as a locking means.

It is also an object of this invention to provide a flyer which can be readily assembled and disassembled and which cannot be placed in operation until the several parts are respectively placed in their correct operating positions.

These and other desirable objects of the present invention will be described in the accompanying specification and illustrated

in the drawings, certain preferred embodiments being shown by way of illustration only, for since the underlying principles may be applied to other specific devices, it is not intended to be limited to the ones here shown except as such limitations are clearly imposed by the appended claims.

In the drawings like numerals refer to similar parts throughout the several views, of which:

Figure 1 is an elevation of the improved flyer mounted on a spindle;

Fig. 2 is a top plan view of the construction shown in Fig. 1;

Fig. 3 is a vertical section taken through the median plane of the improved flyer;

Fig. 4 is a plan view partly in section taken on the line 4-4 of Fig. 3;

Fig. 5 is an elevation of the spindle engaging spring;

Fig. 6 is an elevation of the upper portion of the flyer body;

Fig. 7 is an elevation of the lower portion of the flyer body;

Fig. 8 is a modification of the construction shown in Fig. 7; and

Fig. 9 is an elevation of the modified spring member.

Referring now to the drawings, there is shown a conventional spool or bobbin 1 mounted on a spindle 2. The novel flyer of the present invention, designated generally as 3, is mounted on the spindle and attached thereto by means of spring member 4 whose function will be averted to more in detail hereinafter. The flyer body of the member 3 is preferably made of any suitable metal such as brass, bronze or the like, the several parts being machined to shape or otherwise formed and comprises an upper portion 5 and a lower portion 6. Member 5 comprises a cylindrical body portion having a central aperture 7 provided with a shoulder portion 8 adapted to retain spring member 4 in place. The member 5 is provided with flanges 9, 10, the latter being adapted to abut against shoulder 11 of member 6. In addition, member 5 is provided with a threaded extension 12, adapted to engage a corresponding female thread 13 in member 6.

100

The member 6 is provided with a central aperture 14 and an internally shouldered portion 15 adapted to serve as a stop for member 5 when screwed in place. Integral with portion 11, the socket or casing member 6 is provided with an annular extension 16 adapted to receive flange 10 of member 5. In addition, member 16 is provided with a plurality of diametrically positioned slots 17 having laterally extending portions 18 adapted to receive sections 21 of flyer wires 20 and hold them in position. While the apertures 18 have been shown as substantially horizontal they may of course be given any desired configuration as shown at 19 in Fig. 8 in which they are slanted downwardly and inwardly from the aperture or slot 17.

The flyer wires 20 are provided with a central semicircular bowed portion 22 adapted to engage or abut against section 7 of the flyer holder and is further adapted to be locked in position in the apertures 18 and/or 19. The flyer wires may be inserted in position by passing the bowed portion 22 into the gap or space 23 formed between the abutting parts 5 and 6 of the flyer block. After passing the bowed portion in this manner, a portion 21 of the wire is forced into engagement with section 18 of the retaining slots and the opposite section 21 of the same wire is forced into corresponding engagement with a like slot member. It will be seen that the leverage afforded by the bearing of the portion 22 against the member 7 and of section 21 against portion 16 of the cooperating part of the flyer device will maintain the members locked together due to the fact that the flyer wire engaging flange 10 will prevent the unscrewing of the parts, thus serving as a key or locking member.

When it is desired to unscrew the parts of the flyer block for any reason it will be sufficient to force both of the flyer arms out of engagement with their respective sockets and upwardly into slot 17 and out through aperture 23. As intimated hereinabove, a plurality of flyer wires may be applied, as is indicated in Fig. 4. In this instance, it is merely necessary to provide the slot 17 in member 16 with oppositely positioned depressions or re-entrant portions 18, 19.

The flyer wires are provided with the usual eyes 24, formed at the end of the depending sections 25 of members 20. Owing to the fact that flyer wires wear out at the eyelet portions only under normal working conditions due to the abrasive action of the threads, the present invention comprehends the idea of providing such sections of the flyer wires with a coating of an abrasion resisting metal such as chromium metal or the flyer wires may be formed of a potentially hardenable metal which is manipulated and formed in the usual manner after which the sections 24 may

be subjected to any desired treatment whereby to give them a differential hardness.

Referring now to the spring members 4, it will be noted that they are freely movable within the central portion of the flyer block 70 and are held from axial movement by the shoulders 8 and 15 of the block. The spring member 4, as above indicated, is adapted to engage spindle 2 and revolve therewith the section 7 of the flyer block serving as a bushing or cage upon which the flyer and its associated wires are adapted to freely revolve about the member 4.

While a spiral spring construction may be used, the invention also comprehends the use 80 of a coiled flat spring of the general type shown in Fig. 9. This construction comprises a coiled spring 26 having a centrally offset portion 27, adapted to receive the ends 28, 29 of the spring and present a uniform internal and external diameter.

It will now be appreciated that there has been provided an improved flyer construction comprising a plurality of mutually interlocking parts which are severally replaceable at 90 will and which are characterized by a high degree of mechanical efficiency as well as comparative ease of manufacture and replacement. In addition, there has been provided an improved flyer wire having a wear resistant section at the point where normal break down, due to abrasion occurs.

In accordance with the provisions of the patent statutes, I have described the principles of operation of my invention, together 100 with the device which I now consider to represent a preferred embodiment thereof; but I desire to have it understood that the device shown is only illustrative of the basic concept of the present invention, and that the said 105 invention may be carried out by other means.

I claim:

1. A flyer for the spindles of spinning machines, including an apertured bottom member having an internally threaded extension 110 formed with a shoulder, a threaded apertured top member having a shoulder, and a spring member disposed in said apertures and retained by said shoulders.

2. A flyer for the spindles of spinning machines, including an apertured tubular member having an internal shoulder at one end, an annular groove on the outside of said tubular member, and a threaded extension at one side of said groove adapted to engage a removable cap.

3. A flyer for the spindles of spinning machines, including an apertured tubular member provided with an internal shoulder at one end, and a plurality of external flanges 125 integral with said tubular member and defining an annular channel therebetween.

4. A flyer for the spindles of spinning machines, including an apertured tubular member provided with a plurality of paral-

5   lel external flanges defining an annular groove therebetween, and a threaded extension laterally disposed with respect to one of said flanges and adapted to engage a removable cap.

10   5. A flyer for the spindles of spinning machines including a pair of nested members, a central aperture in said members, opposed slots in the outer of said members, and a flyer wire disposed between the members and held in operative position by the conjoint action of said slots and said inner member.

15   6. A flyer including a bipartite body portion comprising nested members, at least one of said members being removable, the inner member having an external wire receiving annulus and the outer member having a slotted flange cooperating with said annulus.

20   7. A flyer including a bipartite body having a central aperture, inwardly disposed shoulders at the ends of said aperture, a hollow spring member loosely disposed in the bushing formed by said aperture and shoulders; external flanges on the body members, and means formed in one of said members to hold a flyer wire in bearing engagement with the other member.

25   8. A flyer including a nested bipartite body having a central aperture, a flange on the outer of said body portions having wire receiving and locking apertures; a plurality of lateral flanges on the inner body portion forming a wire receiving annulus, and a flyer wire held in position by said inner and outer members, and serving in turn as a locking device for said members.

30   9. A flyer including a nested bipartite body having a central aperture, a flange on the outer of said body portions having wire receiving and locking apertures; a plurality of lateral flanges on the inner body portion forming a wire receiving annulus, a flyer wire disposed in said annulus and engaging said locking apertures whereby to prevent disengagement of the parts.

35   10. In a flyer, in combination, a centrally apertured bipartite body including a pair of nested members, threaded means on said members for mutual engagement, a spring disposed in said central aperture, lateral external flanges on the inner member, a lateral flange on the outer member having a vertical cylindrical extension, slots in said cylindrical extension, and a flyer wire disposed between the inner lateral flanges and held in tension by the slots in the said extension.

40   11. A flyer including a spindle engaging expansible member, a bipartite flyer block screwed over said member and adapted to move freely thereon, and a flyer wire disposed in and between the block segments and forming a locking means therefor.

45   12. A flyer including a body having a centrally apertured hub portion and an outer

sheath adapted for threaded engagement with said hub.

13. A flyer including a body having a centrally apertured hub portion and an outer sheath adapted for threaded engagement with said hub and a movable spindle engaging means in said hub. 70

14. A flyer, including a centrally apertured hub portion, a freely movable expansion member disposed in said aperture, an external flange on said hub, wire receiving slots in the flange and a second member adapted to engage said hub and flange in clamping engagement. 75

15. A flyer, including a body having a centrally apertured hub portion and an outer sheath portion adapted for threaded engagement with said hub, means on said hub for receiving flyer wires, and means on said sheath for bearing engagement with said hub and said wires. 80

85   In testimony whereof I affix my signature.
MICHAEL J. McHALE.
